UNITED STATES PATENT OFFICE.

CHARLES B. ROYAL, OF CHICAGO, ILLINOIS.

LUBRICATOR FOR RAILWAY JOURNAL BOXES.

Application filed August 21, 1926. Serial No. 130,618.

This invention relates to lubricators for railway journal boxes and the like.

An object of the invention is to provide a lubricator of this character which can readily be inserted into and withdrawn from a standard railway car journal box, and one which at the same time is simple and economical to build, which is rugged and not easily gotten out of order, and which will provide constant and ample lubrication for the journal under which it is placed.

Heretofore it has been common practice to pack these journal boxes with waste and oil and to depend upon the capillary action of the waste to carry the necessary oil to the journal.

The present invention replaces that crude method of lubrication by one which is much more efficient and economical and which requires much less labor and inspection to keep it in proper working order.

This and other objects as will hereinafter appear are accomplished by this invention which is fully described in the following specification and shown in the accompanying drawings, in which:

Figure 1 is a vertical longitudinal section through a standard railway journal box;

Fig. 2 is a transverse vertical section on the line 2—2 of Fig. 1;

Fig. 3 is a top plan view of the lubricator showing part of the felt covering removed;

Fig. 4 is a view partly in section on the broken line 4—4 of Fig. 3;

Fig. 5 is a front end elevation of the complete lubricator;

Fig. 6 is a similar view of the lubricator support;

Fig. 7 is a longitudinal vertical section on the line 7 of Fig. 8 of a modified form of the device adapted for use on locomotive journal boxes; and

Fig. 8 is a transverse vertical section on the line 8 of Fig. 7.

The embodiment shown in Figs. 1 to 6 inclusive consists of a removable lubricating device A shown separately in Figs. 3, 4 and 5 which is so made as will hereinafter be explained as to enable it to be readily inserted into a standard railway journal box B with a journal of a standard railway axle C in place therein.

The lubricator has a hollow body 10 which is relatively deep at the outer end and shal-

low at the inner end 11 so as to make it readily insertable into the journal box. This hollow body is covered with wool felt or the like 12 which is held thereon in any suitable manner as by means of a strap 13 passed around it and secured in place by means of screws 14.

Two spaced longitudinally disposed bars 15 are yieldably carried on springs 16. When the lubricator is in place in the journal box these bars press the felt cover 12 against the bottom of the journal C. It will be understood, of course, that the weight of the car is transmitted to the journal C through the journal brass B¹ as shown in Figs. 1 and 2. A sponge, wool or the like 17 is placed in the bottom of the lubricator so as to carry oil therein to the felt 12 with which it is in contact. Oil is fed to the lubricator through either of the two lateral spouts 18, the tops of which are closed by means of hinged lids 19 which are normally held closed by means of springs 20.

The body of the lubricator is provided with rounded longitudinally disposed leaf springs 21 which are secured at the inner end 80 by means of screws or rivets 22, the outer end preferably bearing upon the bottom of the hollow body 10, but free to slide thereon. A spring 23 is also secured to the inner end 85 of the body by means of a screw 24 or the like so that the ends of the spring bear upon the bottom of the journal box housing.

The outer end of the lubricator is carried by a support 25 as shown best in Figs. 5 and 6 which has leaf springs 26 at the bottom which bear upon the bottom of the journal box housing while at the upper corners are provided notches or the like 27 which are adapted to engage pins 28 which extend outward from the forward end of the lubricator body. A screw 29 is then inserted through the support 25 to fasten it to the lubricator body 10 to prevent it from becoming dislodged therefrom.

To remove the lubricator from the journal box as shown in Figs. 1 and 2, the operator lifts up on the journal box cover B², swinging it about the pin B³ until he has access to the inside of the journal box. He then removes the screw 29, at the same time lifting up on the outer end of the lubricator body while pressing down on one end of the support 25 until one of the notches 27

can be swung clear of the pin 28. The other notch 27 is then freed from its pin 28 in the same way after which the support 25 is removed from the journal box. The operator then depresses the outer end of the lubricator body so as to bring the shoulder 30 below the bottom of the collar C¹ on the outer end of the journal C. He then reaches in with one hand on each side of the journal and depresses the inner end of the lubricator body, flattening springs 21 and 23 at the same time slipping the lubricator body around under the collar C¹. The shape of the body as shown, being deeper at the outer end than at the inner, facilitates this movement at the same time forming a reservoir of ample size for oil.

To insert the lubricator into the journal box, exactly the opposite of this operation is performed, the lubricator body being inserted beneath the journal C, the springs 21 and 23 pressing it up against the bottom of the journal, the shoulder 30 on the lubricator fitting in back of the collar C¹ so as to insure its proper position on the journal. It will be understood, of course, that the lubricator will be somewhat shorter than the bearing portion of the journal so as to permit the necessary endwise play of the journal. With the lubricator body in this position, the support 25 is then inserted and secured by means of the screw 29. Oil may then be added through either the channels 18 until these channels are substantially full to the top, the felt 12 serving to retain the oil except where the felt comes in contact with the bottom of the journal C.

Thus, it will be seen that the lubricator body is pressed upwardly toward the journal by means of the springs 21, 23 and 26, while the lubricator body itself is held away from the journal by the action of the springs 16 so that the lubricator body is virtually floating between these two sets of springs which materially lessens the danger of breakage due to the severe road shocks and pounding which are always incident to a railway journal. The side springs 34 take the side thrust of the bearing.

By the use of two spaced bars 15, pressure is applied to the felt cover 12 at two points leaving a somewhat depressed portion of the cover therebetween which acts to catch and hold oil. Thus an ample supply of oil is supplied for the bearing, the cleanliness of the oil being insured by the fact that it is kept within the reservoir in the body 10 to which no grit and dirt is able to find its way due to the felt covering 12 and a tight fastening thereon.

If desired, those portions of the cover 12 which are not in contact with the journal may be treated in any desired manner so as to render them impervious to oil so as to further insure the seepage of the oil

through the cover except where the lubricant is desired.

In Figs. 7 and 8 is shown a modification of the device adapting it to be used on the journals of the main driving axles of locomotives. In this case, the problem of insertion into a very cramped space is not present, the lubricator body 10^a of the bearing housing 31 being insertable from beneath after which the housing 31 is secured in place by means of bolts 32 or the like. Oil is fed to the lubricator through a pipe 33. If desired this may be carried up to a sight feed oil cup. The construction and operation of the lubricator however is very much the same. A felt cover 12^a is secured on the body 10^a by means of a band 13^a and screws 14^a. It will be understood, however, both in this form and in that shown in the other figures that any suitable means may be employed for fastening the felt covers 12 and 12^a in place upon the lubricator bodies.

Parallel bars 15^a are yieldably pressed upward by means of a leaf spring 16^a or the like and a sponge, wool or the like 17^a is used as a yieldable capillary means for conveying oil from the bottom of the lubricator body to the inside of the felt cover 12. Any suitable form of spring 23^a may then be used for holding the lubricator up in contact with the bottom of the journal. It will be observed that the bars 15 and 15^a are spaced far enough apart that these do not press the felt above them directly upon the shaft, but at one side of it.

The lubricator body as shown is a casting, but it will be understood that this device lends itself very readily to a pressed steel construction.

While I have shown and described but two embodiments of my invention it is to be understood that it is capable of many modifications. Changes therefore in the construction and arrangement may be made which do not depart from the spirit and scope of the invention as disclosed in the appended claims.

I claim:

1. In a lubricator for railway journal boxes, an oil reservoir adapted to pass into and out of a journal box with the journal in place therein, an oil transmitting pad adapted to contact the underside of the journal and secured to said reservoir so as to close the top of the same, a spring means for yieldably pressing said reservoir upwardly, and yieldable means within the reservoir for pressing said pad into contact with the underside of the journal.

2. In a lubricator for railway journal boxes, an oil reservoir adapted to pass into and out of a journal box with the journal in place therein, an oil transmitting pad adapted to contact the underside of the journal and secured to said reservoir so as

to close the top of the same, a spring means for yieldably pressing said reservoir upwardly, one spring extending longitudinally of the journal box to assist in the insertion and withdrawal of the lubricator, and yieldable means within the reservoir for pressing said pad into contact with the underside of the journal.

3. In a lubricator for railway journal boxes, an oil reservoir adapted to pass into and out of a journal box with the journal in place therein, an oil transmitting pad adapted to contact the underside of the journal and secured to said reservoir so as to close the top of the same, a spring means for yieldably pressing said reservoir upwardly, and a sponge within the reservoir for pressing said pad into contact with the underside of the journal.

4. In a lubricator for railway journal boxes, an oil reservoir adapted to pass into and out of a journal box with the journal in place therein, an oil transmitting pad adapted to contact the underside of the journal and secured to said reservoir so as to close the top of the same, a spring means for yieldably pressing said reservoir upwardly, laterally spaced longitudinally disposed bars within said reservoir, and springs adapted to press said bars upwardly so as to hold said pad against the lower surface of the journal.

5. In a lubricator for railway journal boxes, an oil reservoir adapted to pass into and out of a journal box with the journal in place therein, an oil transmitting pad adapted to contact the underside of the journal and secured to said reservoir so as to close the top of the same, a spring means for yieldably pressing said reservoir upwardly, laterally spaced longitudinally disposed bars within said reservoir, springs adapted to press said bars upwardly so as to hold said pad against the lower surface of the journal, and capillary means between said bars for feeding oil from said reservoir to the underside of said pad.

6. In a lubricator for railway journal boxes, an oil reservoir adapted to pass into and out of a journal box with the journal in place therein, an oil transmitting pad adapted to contact the underside of the journal and secured to said reservoir so as to close the top of the same, a spring means for yieldably pressing said reservoir upwardly, laterally spaced longitudinally disposed bars within said reservoir, springs adapted to press said bars upwardly so as to hold said pad against the lower surface of the journal, and a sponge between said bars for feeding oil from said reservoir to the underside of said pad.

7. In a lubricator for railway journal boxes, an oil reservoir adapted to pass into and out of a journal box with the journal in

place therein, an oil transmitting pad adapted to contact the underside of the journal and secured to said reservoir so as to close the top of the same, a member detachably secured to said reservoir for supporting the outer end of the same in raised position and yieldable means within the reservoir for pressing said pad into contact with the underside of the journal.

8. In a lubricator for railway journal boxes, an oil reservoir, a felt cover tightly secured thereon, means for feeding oil to the underside of said cover, spaced bars within said reservoir for yieldingly pressing said cover against the underside of a railway journal, and springs on the bottom of said reservoir for holding said cover up in contact with said journal.

9. In a lubricator for railway journal boxes, an oil reservoir, a felt cover tightly secured thereon, means for feeding oil to the underside of said cover, spaced bars and springs within said reservoir for yieldingly pressing said cover against the underside of a railway journal, and springs on the bottom of said reservoir for holding said cover up in contact with said journal.

10. In a lubricator for railway journal boxes, an oil reservoir, a felt cover tightly secured thereon, means for feeding oil to the underside of said cover, means within said reservoir for yieldably pressing said cover against the underside of a railway journal, and springs on the bottom of said reservoir for holding said cover up in contact with said journal.

11. In a lubricator for railway journal boxes, an oil reservoir adapted to pass into and out of a journal box with the journal in place therein, an oil transmitting pad adapted to contact the underside of the journal and secured to said reservoir so as to close the top of the same, a spring means for yieldably pressing said reservoir upwardly, laterally spaced longitudinally disposed bars within said reservoir, and springs adapted to press said bars upwardly so as to hold said pad against the lower surface of the journal, said bars being located far enough at the sides of said journal to prevent the pad being pressed between said journal and bars.

12. In a lubricator for railway journal boxes, an oil reservoir, a felt cover tightly secured thereon, means for feeding oil to the underside of said cover, spaced bars within said reservoir for yieldably pressing said cover against the underside of a railway journal, and springs on the bottom of said reservoir for holding said cover up in contact with said journal, said bars being located far enough at the sides of said journal to prevent the pad being pressed between said journal and bars.

13. In a lubricator for railway journal

boxes, an oil reservoir, a felt cover tightly secured thereon, means for feeding oil to the underside of said cover, spaced bars within said reservoir for yieldably pressing said cover against the underside of a railway journal, springs on the bottom of said reservoir for holding said cover up in con-

tact with said journal, and means for maintaining an oil level above the level of said felt cover.

In witness whereof, I have hereunto set my hand this 14th day of August, 1926.

CHARLES B. ROYAL.
